W. H. TAYLOR, OF BALDWINSVILLE, NEW YORK.

Letters Patent No. 79,874, dated July 14, 1868.

IMPROVED HARNESS-BUCKLE.

The Schedule referred to in these Letters Patent and making part of the same.

TO ALL WHOM IT MAY CONCERN:

Be it known that I, W. H. TAYLOR, of Baldwinsville, in the county of Onondaga, and State of New York, have invented a new and improved Harness-Buckle and Loop combined; and I do hereby declare that the following is a full, clear, and exact description thereof, which will enable those skilled in the art to make and use the same, reference being had to the accompanying drawings, forming part of this specification, in which—

Figure 1 is a front view of my invention,

Figure 2 is a side view, and

Figure 3 is a sectional side view.

Figure 4 shows the ordinary leather loop.

Similar letters of reference indicate like parts in all the figures.

This invention consists in constructing harness-buckles in such manner that the frame of the buckle shall fill the place of both buckle-frame and loop. The ordinary leather loop is either stamped out or worked up by hand, but those of the best quality are made wholly by hand-labor, as the ornamental design and form have greater endurance than by the stamping method, and consequently considerable labor is involved in its construction. But by this construction the loop is made of metal, being cast as a part of the buckle, and any design which is cast thereon is permanent and the loop always retains its form; also, a desirable saving in leather is made. By japanning these loops they are made to represent leather, but they can be made with an X-silvered (tinned) or other suitable metallic finish.

In the accompanying drawings, A is the ornamental face of the loop or buckle-frame, and B is the body of the same. C represents the hames-tug, f is the breeching-loop, and g g are the side loops for the back and belly-straps. The face or cover A is made separate from the body B, and is hinged to the body at d d. The tongues of the buckle are formed by two studs, a a, which project from the inner face of cover A, as shown in fig. 3. These tongues may be one or more, as desired. A portion, A', of the cover is made separate from the main portion, and is hinged to the body at h. b b are cross-bars on the rear side of the buckle.

It is operated as follows: When the tug is to be taken up or let out, the cover A is thrown back to withdraw the tongues a a from the tug, and when the tug has been brought to the proper position, the cover A is turned down, and its tongues engaged with the tug, and section A' of the cover, fig. 3, is then closed down and laps on to A, so as to secure it in its closed position. However, I do not wish to confine myself to this particular method of securing the tongue-bearing cover A. The side loops g g are dispensed with in light harness, and their straps secured to the hames-tug immediately in front of the buckle and loop.

As the buckle is out of sight, the device gives a snug appearance, and a neat and durable loop is obtained, and at a less cost than heretofore.

Having thus described my invention, what I claim as new, and desire to secure by Letters Patent, is—

The combination of buckle and loop, substantially as and for the purpose specified.

The above specification of my invention signed by me, this 28th day of April, 1868.

W. H. TAYLOR.
